(57) **CLAIM**

The ornamental design for a transfer robot, as shown and described.

DESCRIPTION

1. Transfer robot
- 1.1 : Perspective
- 1.2 : Front
- 1.3 : Back
- 1.4 : Left
- 1.5 : Right
- 1.6 : Top

The broken lines shown in the figures depict portions of the transfer robot that form no part of the claimed design; the bottom view is omitted since the bottom of the product is hardly seen in use.
